J. L. FAY,
COMBINED CHOKE COIL AND FUSE,
APPLICATION FILED APR. 19, 1918.

1,284,629.

Patented Nov. 12, 1918.

UNITED STATES PATENT OFFICE.

JOHN L. FAY, OF ST. LOUIS, MISSOURI.

COMBINED CHOKE-COIL AND FUSE.

1,284,629.

Specification of Letters Patent.

Patented Nov. 12, 1918.

Application filed April 19, 1918. Serial No. 229,558.

To all whom it may concern:

Be it known that I, JOHN L. FAY, a citizen of the United States, residing at St. Louis, Missouri, have invented a certain new and useful Improvement in Combined Choke-Coils and Fuses, of which the following is a full, clear, and exact description, such as will enable others skilled in the art to which it appertains to make and use the same, reference being had to the accompanying drawings, forming part of this specification.

My invention relates to a combined choke coil and fuse such as is ordinarily used in transmission lines or distribution circuits for the protection of transformers and like equipment, my present invention being an improvement on the combined choke coil and fuse disclosed in my Patent No. 1,187,894, issued June 20, 1916.

The principal objects of my present invention are, to generally improve upon and simplify the construction of the choke coil and fuse disclosed in my patent aforesaid; to provide simple and efficient means for effecting a thorough insulation of the choke coil; to provide for the ready escape of the flames against a relatively high degree of pressure produced thereby when the fuse forming a part of the device is burned out as a result of overload or for any other causes; to provide a construction wherein the fuse may be easily and quickly placed in proper position for use; to provide a combined choke coil and fuse which can be easily and cheaply manufactured, which is very compact, and highly efficient in service; and further, to provide a construction which will afford a relatively high degree of safety to the repairmen while the fuse carrying member is being removed from or inserted in the coil housing.

With the foregoing and other objects in view, my invention consists in certain novel features of construction and arrangement of parts, hereinafter more fully described and claimed, and illustrated in the accompanying drawings, in which—

Figure 1 is a vertical section taken through the center of an improved choke coil and fuse of my improved construction.

Fig. 2 is a horizontal section taken approximately on the line 2—2 of Fig. 1.

Fig. 3 is a detail section taken approximately on the line 3—3 of Fig. 1.

Fig. 4 is a plan view of a bracket that is

utilized for supporting the choke coil and fuse on a cross arm or the like.

Referring by numerals to the accompanying drawings, 10 designates an inverted cup-shaped housing or shell, the same being constructed of suitable insulating material such as glass or porcelain, and the lower portion of this shell or housing is flared outwardly as designated by 11 to form an apron.

Formed in the outer face of the body of the housing 10 is a circumferentially disposed groove 12 which is adapted to be occupied by straps or bands 13 and 14, the same being secured to each other in any suitable manner and the band 14 being provided with legs 15 which are secured to a cross arm or the like, thus providing a firm and substantial support for the housing 10 and parts carried thereby.

Arranged within the housing 10 is a second housing or shell 16 of asbestos, glass, porcelain or other insulating or fire-resistant material, said inner housing being closed at its upper end and provided at its lower end with an integral flange 17. Formed in the outer face of this shell or housing 16 is a spirally disposed groove 18 in which is seated a conductor 19 of suitable metal, preferably copper, one end of this conductor being extended downward over the edge of flange 17 and being electrically connected to a pair of contact plates 20, the inner portions thereof being spaced apart in order to receive a single contact member carried by the removable plug forming a part of the device.

The housing 16 carrying the coil 19 is secured to housing 10 by a layer or wall 21 of suitable cement, the same being formed of fire-proof material or material which is not affected by relatively high degrees of heat.

The wire or conductor forming the coil on housing 16 is extended downward from the upper end of said housing through this wall or layer of cement as designated by 22 and embedded in said cement and interposed between the portion 22 and the adjacent coils is a vertically disposed strip 23 of mica or analogous material. The lower end of portion 22 of the conductor projects downwardly from the lower end of the wall or layer of cement and thence passes outwardly beneath the apron 11 to be connected to the line conductor.

The construction just described provides

means for very firmly anchoring the housing 16 within the outer housing 10 and likewise for protecting the choke coil located in the spiral groove 18.

5 Secured in any suitable manner to the underside of flange 17 and disposed directly opposite to the pair of contact plates 20 is a pair of contact plates 24, the ends thereof being preferably spread apart as 10 illustrated in Fig. 3 in order to receive an outwardly projecting contact member carried by the removable plug forming a part of the device.

Suitably connected to these contact plates 15 24 is one of the terminals 25 of the line conductor.

The removable plug or fuse carrying member includes a handle 26 of porcelain, glass or analogous material, the same being 20 provided with an axially disposed bore or passageway 27. Formed integral with the lower end of this handle 26 is an outwardly projecting flange 28 and formed integral with the upper end of said handle is an 25 outwardly projecting relatively wide flange 29, the same being adapted to overlie the contact plates 20 and 24 when the removable member is properly inserted in the coil carrying housing.

30 Secured in any suitable manner to the upper end of handle 26 is a plug 30 of asbestos or analogous fire-resisting material, and formed diametrically through this plug is an aperture 31, the same communicating 35 with the upper end of a bore or passageway 32, the lower end of the latter communicating with the upper end of the bore or passageway 27.

Secured in any suitable manner to the 40 upper portion of handle 26 above the flange 29 are oppositely arranged contact plates 33, the same being adapted to engage between the pairs of contact plates 20 and 24.

Formed in the outer face of the plug 30 45 and on opposite sides thereof is a longitudinally disposed groove 34, the same serving as a seat for the fuse 35, the ends of the latter being connected in any suitable manner to contact plates 33.

50 It will be noted that the aperture 31 is disposed at right angles to the plane occupied by the fuse 35 when the latter is properly positioned in groove 34, and consequently it will be impossible for portions 55 of the fuse to arc through said opening 31 when said fuse explodes or burns out.

When the fuse carrying member comprising the handle 26 and plug 30 is to be positioned in the coil carrying housing, the 60 operator grasps the handle 26 between the flanges 28 and 29 and moves the plug 30 upwardly into the chamber within housing 16 during which time the hand of the operator is protected against the contact of 65 plates 20 and 24 by the relatively wide

flange 29. This upward movement is continued until contact plates 33 strike against the underside of flange 17 whereupon the handle is rotated until the contact plates 33 pass between the pairs of contact plates 20 70 and 24, and thus the fuse and choke coil are brought into circuit with the terminals of the line in which the device is located.

In the event that the fuse carried by the plug 30 blows out, the flame and gases resulting from such blow-out will find ready exit through opening 31 and from thence downwardly through passageways 32 and 27.

It will be understood that the blowing-out of a fuse creates a relatively high degree of pressure and that this pressure would be destructive to parts of the device were it not for the fact that the relatively large openings 31, 32 and 27 provide escape for such pressure, thereby nullifying its destructive tendencies.

When in service, my improved device is located on a suitable support or cross arm adjacent to a transformer or other apparatus and when so positioned, said transformer or apparatus is effectively protected against sudden rushes of current which may come in on the line as a result of lightning discharge, for the choke coil disposed upon the housing 16 has the effect of damping or 95 choking the rush of current, thereby preventing strain on the transformer windings, reducing break-down of the transformer insulation, and likewise preventing the interruption of service to consumers of current. 100 The relatively wide flange 29 at the upper end of the handle 26 serves as a closure for the chamber in housing 16 and consequently the plug 30, the fuse carried thereby, and the contact plates 20 and 24 are effectively 105 protected against rain, snow, ice and the like. Likewise this wide flange serves to protect the hand of the repairman while the plug is being placed in position within or removed from the coil housing.

A device of my improved construction is comparatively simple, can be easily and cheaply manufactured, and provides an efficient protection for transformer and like devices against abnormal and destructive 115 currents coming in over a transmission line or distribution circuit.

It will be readily understood that minor changes in the size, form and construction of the various parts of my improved choke coil and fuse may be made and substituted for those herein shown and described, without departing from the spirit of my invention, the scope of which is set forth in the appended claims.

I claim:

1. In a device of the class described, an outer housing, a hollow member within said outer housing, a choke coil on said hollow member, a body of insulation inclosing said 120

125

130

choke coil and disposed between the hollow member and the housing, and a fuse carrying plug removably positioned within said hollow member.

5. 2. In a device of the class described, an outer housing, a hollow member within said outer housing, a choke coil on said hollow member, a body of insulation inclosing said choke coil and disposed between the hollow member and the housing, a fuse carrying plug removably positioned within said hollow member, and means carried by said plug and hollow member for making contact between the choke coil and the fuse carried by 15 said removable plug.

3. In a device of the class described, a housing, a choke coil embedded in the wall of said housing, a fuse carrying plug adapted to be removably positioned in said 20 housing, and means ~~on~~ said plug and the housing for making contact between said choke coil and the fuse carried by said removable plug.

4. In a device of the class described, inner 25 and outer housings, a choke coil wound upon the inner housing, a plug adapted to be removably positioned within said inner housing, a fuse carried by said plug, means on said plug and the inner housing for establishing communication between the fuse 30 and choke coil, and said plug being provided with an opening to permit the discharge of the flames and gases resulting from the blowing of the fuse.

35. 5. In a device of the class described, a housing, a choke coil therein, a member adapted to be removably applied to said housing, a plug carried by said member and adapted to enter the housing, a fuse carried 40 by said plug, means for making contact between said fuse and choke coil, and there being openings formed in said removable member and plug carried thereby.

6. In a device of the class described, a 45 housing, a hollow member arranged within

said housing, a choke coil on said hollow member, and a body of insulating material inclosing said choke coil and occupying the space between the hollow member and the housing and serving to unite said housing 60 and hollow member.

7. In a device of the class described, a housing, a choke coil therein, a member adapted to be removably positioned on the housing, said member comprising a handle 55 and a plug of fire-resisting material, a fuse carried by said plug, and there being openings in said plug and handle to permit the escape of flames and gases from the chamber in the housing occupied by the plug and 60 fuse carried thereby.

8. In a device of the class described, a housing of fire-resisting material, a choke coil embedded in the wall of said housing, a member adapted to be removably positioned 65 in said housing, said member being formed of fire-resisting material, a fuse carried by said member, means for forming a connection between said fuse and choke coil when the member is applied to the housing, and 70 said removable member being provided with an opening to permit the escape of flames and gases from the chamber occupied by said member and the fuse carried thereby.

9. In a device of the class described, a 75 housing, a choke coil within said housing, the main body portion of which choke coil is covered by insulating material, a member adapted to be removably positioned in said housing, a fuse carried by said removable member, said removable member being provided with an opening to permit the discharge of flame and gases resulting from 80 the blowing of the fuse, and means for making contact between said fuse and choke 85 coil.

In testimony whereof I hereunto affix my signature this 16th day of April, 1918.

JOHN L. FAY.
